UNITED STATES PATENT OFFICE

JOSEPH MUROS, OF NEW YORK, N. Y., ASSIGNOR, BY MESNE ASSIGNMENTS, TO GILLETTE SAFETY RAZOR COMPANY, OF BOSTON, MASSACHUSETTS, A CORPORATION OF DELAWARE

SAFETY RAZOR

Application filed June 22, 1928, Serial No. 287,545. Renewed August 25, 1932.

The present invention relates to improvements in safety razors, and more particularly to the blade holder and blades thereof.

It is a common practice at present in the safety razor trade to manufacture and sell blades which fit the blade holders of other manufacturers. The user may, therefore, purchase several makes of blades fitting his blade holder to the exclusion of the blades manufactured by the maker of the holder. While under certain circumstances there is nothing wrong with this practice, an extended study of the field reveals the fact that the general public is apt to blame the manufacturer of the holder for the faults of inferior blades, resulting in great injury and damage to the reputation of the holder manufacturer.

The main object of the present invention is to provide a blade holder and blade construction which effectively precludes this general practice.

Another object of the invention is to provide a simple and efficient blade holder and blade construction which is capable of manufacture on a commercial scale, or in other words one which is not so difficult to make as to be beyond the reasonable cost of such a contrivance.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

A few of the many possible embodiments of the invention are illustrated in the accompanying drawings, in which:—

45 Figure 1 is a front elevation of a safety

razor constructed in accordance with the present invention; Fig. 2 is a section taken on line 2—2 of Fig. 1; Fig. 3 is a top plan view of the blade supporting element of the razor; Fig. 4 is a bottom plan view of the blade 50 clamping element thereof; Fig. 5 is a section taken on line 5—5 of Fig. 4; Fig. 6 is a portion of a section taken on line 6—6 of Fig. 2; Fig. 7 is a section taken on line 7—7 of Fig. 5; Fig. 8 is a plan view of the improved blade, 55 showing the blade positioning lugs of the holder in operative relation to elements of the blade co-operating therewith; Fig. 9 is a section similar to the one shown in Fig. 2, showing the parts assembled before flexing 60 the blade for use; Fig. 10 is a longitudinal section taken through a modified blade holder and the blade; Fig. 11 is a plan view of the blade supporting and clamping elements of the modified holder; Fig. 12 is a plan view 65 of the blade co-operating with the said modified holder; Fig. 13 is a longitudinal section taken through a portion of a still further modification of the invention; Fig. 14 is a fragmentary top plan view of the blade support 70 of the modification shown in Fig. 13; and Fig. 15 is a plan view of a portion of a blade used in the modification illustrated in Fig. 13.

Referring now first to Figs. 1 to 9, inclusive, of the drawings, which illustrate the 75 application of the invention to a safety razor of the Gillette type, the numeral 20 indicates a blade supporting plate, suitably curved along its longitudinal edges and provided with teeth 21, forming guards for the well known purpose. On this plate is adapted to rest a transversely flexible blade 22, having longitudinal cutting edges 23. This blade is positioned upon its support by lugs 24 on a clamping cap 25, which lugs extend through 80 openings 26 and 27 in the blade and supporting plate, respectively, the said lugs and the said openings being of a configuration to be more fully described hereinafter.

The cap is provided with a concaved under- 85

face 28, its longitudinal edges resting on the upper face of the blade. Centrally projects from the underface of the cap a screw-threaded spindle 25', which extends through registering apertures 29 and 30 in the blade and supporting plate, respectively. The razor is provided with a handle 31, having a screw-threaded bore, not shown, with the threads of which mesh those of the spindle 25'. The construction and operation of the said screw-threaded bore and said spindle are well known, they being of the type embodied in the razor known in the trade as the Gillette razor.

The positioning lugs 24 are each provided at their free ends with an enlarged head 32, the body portion 33 of each lug being cylindrical, although this is not essential. The head 32 of each positioning lug is longitudinally grooved, as indicated at 34, the grooves extending exactly to the perimeter or bounding line of the transverse cross-section of the body portion of the positioning lug. In the case illustrated, of course, the grooves extend to the perimeter of the circle of the transverse cross-section of the body portion of the said lug. The length of the body portion of each lug is such that the said body portion extends into the opening 27 in the supporting plate 20 in the assembled positions of the elements of the razor before flexing the blade as clearly shown in Fig. 9 of the drawings. The purpose of this arrangement will appear hereinafter. From Figs. 2 and 9 it also appears that the length of the body portion of each lug exceeds the thickness of the blade.

The registering openings 27 and 26 in the supporting plate 20 and razor blade 22, respectively, are alike in configuration. They follow closely the contours of the heads 32 of the positioning lugs 24 in the largest cross-sections of the said heads. As appears more specifically from Fig. 8 of the drawings, these openings are substantially star-shaped, although this is not essential, the shape depending entirely on the configuration and arrangement of the grooves in the heads of the positioning lugs. It is, however, essential that each opening 26, no matter of what shape it be, shall be provided with projections 35, which extend toward the center of the opening, all of the projections terminating on the imaginary perimeter or bounding line of a figure which is that of the transverse cross-section of the body portion of the positioning lug co-operating with said opening. As pointed out above, the openings 27 in the supporting plate 20 have the configuration of the openings 26 in the razor blade. This, however, is not essential. The openings 27 may be of circular shape or any other shape to accommodate the largest transverse cross-section of the head of a lug. In any event, it is desirable to make the openings 27 of

a size that the heads of the positioning lugs contact with the said openings all around, in order to prevent relative movement between the heads of the positioning lugs and the supporting plate in all directions in the plane of said supporting plate.

In use, the razor is assembled in the usual manner, Fig. 9 showing the parts assembled before flexing of the blade for shaving. In these positions of the elements the projections 35 in the openings 26 in the blade already abut against the cylindrical body portions of the supporting lugs, so that, when the blade is flexed by screwing home the handle 31, the blade is effectively prevented from shifting either longitudinally or transversely on the supporting plate of the razor, or in any other direction save in the direction of the axes of the positioning lugs.

By reason of the construction of the heads of the positioning lugs and the configuration of the openings 26 in the blade, it is obvious that, if it is attempted to design a blade to fit the razor herein described without having recourse to the projections 35 in the openings 26 in the blade, such blade would have to have openings of a size corresponding to the largest diameter of the head 32 of a positioning lug, but then the said blade would shift on the supporting plate when the handle of the razor is screwed home so as to clamp the blade in shaving position. Of course, if the length of the body portions of the lugs were not as described in connection with Fig. 9 of the drawings, that is to say if the body portion of each lug were not of a length so that the outer end of the said body portion were disposed within an opening 27 in the supporting plate when the elements of the razor are assembled before flexing of the blade for use, the blade would be prevented from shifting on the supporting plate.

The modification illustrated in Figs. 10 to 12, inclusive, of the drawings, differs from the one above described mainly in that the supporting plate 36 and the clamping plate 37 of the razor are joined by a hinge 38, and held in clamping position by a clip 39, or other suitable means. In this case the positioning lugs 40 are mounted upon the supporting plate and project through openings 41 in the blade 42 into openings 43 in the clamping plate 37. The body portions of these lugs are in the case illustrated quadrangular in transverse cross-section, their heads 44 being provided with grooves 45, which are disposed around the bounding figure of the said transverse section. The openings 41 in the blade 42 correspond in configuration to that of the largest cross-sections of the heads 44 of the supporting lugs in the same manner as the openings in the blades of the razor illustrated in Figs. 1 to 9, inclusive, correspond to the largest cross-sections of the heads of the positioning lugs shown therein.

The openings 43 in the clamping plate 37 are in this case quadrangular, fitting the heads of the positioning lugs. Attention is called to the fact that the length of the body portions of the lugs is in this instance such that the said body portions project into the openings 43 in the clamping plates, that is to say into the openings of the element co-operating with the element which carries the said lugs.

10 Otherwise the construction and operation of the elements are the same as of those described in connection with Figs. 1 to 9, inclusive, of the drawings.

The modification illustrated in Figs. 13 to 15, inclusive, includes positioning lugs 46 mounted on one element of the blade holder, for instance on the supporting plate 47, and including a body portion 48 of, for instance, quadrangular cross-section, provided with a head 49 which projects to one side of the body portion only. This head is provided with a single groove 50, which extends exactly to the bounding figure of the transverse cross-section of the body portion of the supporting lug, as clearly appears from Figs. 13 and 15 of the drawings. The blade 51 is in this case provided with an opening 52 of a configuration corresponding to that of the largest transverse cross-section of the head 49, and the clamping plate 53 has an opening 54 to receive the said head. The operation of this modified razor is obvious from the foregoing, the construction differing from those above described only in that the head of the positioning lug projects to one side only of the body portion thereof.

It is, of course, obvious that many other modifications of the head and the openings co-operating therewith are possible without departing from the invention, which lies mainly in the provision of a positioning lug having an enlarged head, provided with one or more longitudinal grooves, co-operating with an opening in the blade provided with projections fitting the grooves and being adapted to contact with the body portion of said lug.

What I claim is:

1. The combination with a blade having 50 one or more openings, of a blade holder, a corresponding number of positioning lugs on said holder for co-operation with said openings, each lug having a body portion and an enlarged head, said head being provided 55 with one or more longitudinal grooves extending to the bounding figure of the transverse cross-section of the body portion of the lug, the configuration of each opening in said blade corresponding to that of the largest 60 transverse cross-section of the head of a lug co-operating therewith.

2. The combination with a blade having one or more openings, of a blade holder, a corresponding number of positioning lugs on said 65 holder for co-operation with said openings,

each lug having a body portion and an enlarged head, said head being provided with one or more longitudinal grooves extending to the bounding figure of the transverse cross-section of the body portion of the lug, each 70 of said openings having one or more projections fitting the grooves in the head of the lug co-operating therewith and being in contact with the body portion of said lug when said blade is positioned on said holder. 75

3. The combination with a blade having one or more openings, of a blade holder, a corresponding number of positioning lugs on said holder for co-operation with said openings, each lug having a body portion and an 80 enlarged head, said head being provided with one or more longitudinal grooves extending to the bounding figure of the transverse cross-section of the body portion of the lug, each opening in said blade having one or more 85 projections adapted to be passed through the grooves in the head of a lug and being in contact with the body portion of the lug when said blade is mounted on said holder.

4. In a combination according to claim 1, 90 the length of the body portion of each lug exceeding the thickness of said blade.

5. In a combination according to claim 2, 95 the length of the body portion of each lug exceeding the thickness of said blade.

6. In a combination according to claim 3, the length of the body portion of each lug exceeding the thickness of said blade. 95

7. The combination with a blade having one or more openings, of a blade holder, a corresponding number of positioning lugs on said holder for co-operation with said openings, each lug having a body portion of the same transverse cross-section throughout its length and an enlarged head and each opening being of a size to permit passage of the head of one of the lugs therethrough, each opening being of a configuration whereby its edge contacts with the body portion of the respective lug at a plurality of spaced points 100 after the head of said lug has passed through said opening. 105

8. A blade for a safety razor having one or more openings adapted to receive positioning lugs on a blade holder provided with enlarged heads, each opening being large enough to permit of passage therethrough of the head of a lug co-operating therewith and each opening having a series of circumferentially arranged projections extending inwardly and defining a circle by their inner edges and arranged to contact at a plurality of spaced points with the body portion of a lug co-operating therewith after the said head has passed through said opening. 115 120 125

9. The combination with a blade having one or more openings, of a blade holder, a corresponding number of positioning lugs upon said holder for co-operation with said openings, each lug having a body portion of the 130

same transverse cross-section throughout its length and an enlarged head with diverging grooves in its periphery and each opening being of a size to permit passage of the grooved head of a lug therethrough, each opening being of a configuration whereby a portion of each edge of the opening contacts with the body portion of the respective lug after the head of said lug has passed through said opening so as to prevent the blade from shifting in its plane in any direction in relation to a lug co-operating therewith when a blade is mounted on said holder.

10. The combination with a blade having one or more openings, of a blade holder, a corresponding number of positioning lugs on said holder for co-operation with said openings, each lug having a body portion and an enlarged head and each opening being of a size to permit passage of the head of a lug therethrough, and a series of circumferentially arranged projections integral with said blade and associated with each opening for symmetrically and directly engaging the body of the lug by point contact upon all sides thereof to prevent the blade from shifting in its plane in any direction in relation to a lug co-operating therewith when the blade is mounted upon said holder.

11. A blade for a safety razor having one or more openings adapted to receive positioning lugs with enlarged heads, each opening being large enough to permit of passage therethrough of the head of the lug co-operating therewith and each opening being provided with a series of equally spaced circumferentially arranged radially extending projections adapted to contact symmetrically with the body of the lug on all sides thereof and positively to locate the blade in the holder.

12. A blade for a safety razor having one or more openings therein adapted to receive positioning lugs having uniformly corrugated heads, each opening being provided with a series of uniformly spaced projections radially converging and terminating at their inner ends in a circle of less diameter than that of the corrugated head.

13. A blade for a safety razor having a blade locating opening therein adapted to receive a positioning lug of substantially circular contour, the opening in the blade being substantially star-shaped and having in its edge a plurality of uniformly spaced inwardly converging projections defining at their inner ends a circle of substantially the same diameter as the lug, whereby the lug may be engaged on all sides by point contact of said projections to prevent shifting of the blade in its plane in any direction.

14. A blade for a safety razor having one or more openings each adapted to receive a positioning lug provided with an enlarged symmetrical head at its free end, each open-

ing being large enough to permit passage therethrough of the head of a lug and each opening having a series of circumferentially arranged projections extending inwardly and defining a circle by their inner edges and arranged to contact with the body portion of a lug at points uniformly distributed about its entire periphery and co-operating therewith after the said head has passed through said opening.

Signed at New York, in the county of New York, and State of New York, this 21st day of June, A. D. 1928.

JOSEPH MUROS.
